UNITED STATES PATENT OFFICE

HARRY S. CORNISH, OF NEW YORK, N. Y.

APPARATUS FOR COOLING AND CARBONATING POTABLE LIQUIDS

Application filed March 21, 1928. Serial No. 263,226.

My invention relates to a method of and apparatus for employing an artificial ice such for instance as CO₂ ice for purposes of refrigeration and utilizing the gas released from the ice in its cooling action to charge a liquid preferably for the purpose of increasing its potability.

As the invention is especially useful in producing a carbonated liquid or soda water I will describe the invention as applied to the production of a liquid charged with carbon dioxide or carbonic gas derived from the melting or evaporation of CO₂ ice or other ice secured by the release of a gas at high pressure containing carbon dioxide or otherwise produced.

In order that the nature of my invention may be more readily understood and distinguished from the prior art a brief reference will be made to prior practice in the art of carbonating liquids and to certain objectionable features thereof which it is the aim of the present invention to avoid.

Carbon dioxide as usually employed for carbonating liquids is shipped in drums or containers under very heavy pressure and in order to carbonate the liquid in a carbonator body or container of such liquid the drum is connected with said carbonator and the contents are released into the carbonator body at a lesser pressure which however may be as much as 120 to 175 pounds pressure, against which pressure pumps are used to force the water or liquid to be carbonated into the body where the CO₂ and water are, in some cases, agitated or stirred by a mechanical mixer operated by any suitable power, as for instance the motor or power which operates the pump.

In some cases the carbonators have no agitator but rely on the pump forcing the water into the carbonator body above the body of water therein and through a spray head which is intended to aid carbonation.

The drums or containers usually employed for the CO₂ contain CO₂ liquefied at about 1000 pounds pressure and when used in connection with the carbonator a reducing valve and gauge is interposed between them to cut down the pressure to say 150 pounds. The

drums are heavy and frequently weigh as much as 110 pounds and carry only 50 pounds of liquid CO₂, a total of about 160 pounds to deliver 50 pounds of CO₂. These tubes or drums being heavy, frequently become damaged giving rise to the necessity for repair, while the return freight must be paid on the empty, and inasmuch as it takes a long time ordinarily to use up the contents, the annual expense of turn-over makes the drums a heavy expense of the business. Furthermore the high pressures bring a heavy strain on the entire system which is particularly objectionable in the case of carbonators from which carbonated liquid is supplied to draft arms of a soda water fountain or to other outlets for other purposes. This high pressure gives rise to costly leaks of carbonated water and CO₂. Also carelessness on the part of the operator may cause the entire pressure in a drum to be suddenly thrown into the serving system with serious results.

On an average, over 2 pounds of liquid CO₂ is returned from the purchaser in an "empty" drum, because if the carbonator is "set" at say 120 pounds, when the pressure in the drum is down to 120, there is still over 2 pounds of CO₂ left in the drum, but the operator must treat it as "empty". Stronger pumps and more current must be used to force the water against these higher pressures in the carbonator. This means also wear on packings and other equipment, leading to costly leaks and replacements.

The mechanical carbonator, with its agitator, is intended to hasten the mixture for use where large volumes of business require big supplies of carbonated water. These pumps are started and stopped by various devices, some using a small tank that fills and empties with the carbonator body, others by balancing the weight of the water in the carbonator body by various devices, the movement of such devices opening and closing the motor switch. None of the present carbonators mix the CO₂ and water outside the carbonator body. The agitators will not provide well-carbonated water if said water is being drawn at the draft arm or on the bottling machine as fast as the pump will supply the water to

the carbonator, and at all times the tendency of the agitator is to knock the CO₂ out of the water about as fast as it is supposed to put it in. Tests prove this.

Present carbonators are connected up (usually, but some have storage water tanks in between) directly to the city water pressure, so that as the city pressure varies the delivery speed (amount of water pumped) of the pump varies. In the present standard carbonator this variation makes no difference (and where a storage tank is used the pressure is constant, same as in my proposed construction) because water is pumped against CO₂ and is agitated. But none of the present carbonators have any means for fixing the proportion of CO₂ and water even where a storage tank is used.

In place of the drums containing CO₂ under heavy pressure, as heretofore employed in the art, I propose to utilize CO₂ in solid form (ice) as a refrigerant for any purpose, as for instance for cooling or icing the liquid to be carbonated after carbonation and to employ the CO₂ released by the evaporation thereof in the cooling action as the gas for carbonating the liquid. Preferably the liquid carbonated by such gas is stored or delivered into a carbonator body or tank ready for use, but it would be within my invention to deliver it directly from the liquid and gas pumps constructed and operated as hereinafter more particularly described. As well understood, CO₂ may be produced in solid form (ice) by releasing the liquid CO₂ in a suitable construction where it turns to "snow" which may be pressed into blocks of desired shape, and so used as a refrigerant, the temperature of such CO₂ solid being 117° below zero 40 Fahrenheit, as compared with water ice temperature of 32° above zero Fahrenheit.

When placed in a chamber to be used as a refrigerant solid CO₂ evaporates and in evaporating produces the refrigeration and, being 45 heavier than air (it may be poured, the same as water) it goes to the bottom of any compartment, forces out the air, until eventually the compartment is filled with evaporated CO₂ when evaporation takes place more slowly. Heretofore such evaporated CO₂ has not been utilized, except to refrigerate, although it is exactly the same as when CO₂ is taken from a drum to be used for carbonation. To utilize this evaporated CO₂ will 50 accomplish at least two things,—lessen the expense of both refrigeration and carbonation, and enable the shipment of solid CO₂ instead of liquid in drums, in a package such as a light paper or cardboard wrapper that may be thrown away, with the consequent big saving in expense. To accomplish this a new construction must be used for the carbonation, for obviously present carbonators have no provision for utilizing this evaporated CO₂, 55 nor even liquid CO₂ without pressure. Where

solid CO₂ is now used as a refrigerant, a drum of liquid CO₂ is required for carbonation.

A part of my present invention relates to the special means whereby the released CO₂ gas which is at comparatively low pressure 70 or any other source of CO₂ gas at low pressure may be brought into contact, at sufficient pressure, with the liquid to be carbonated. This part of my invention comprises essentially a gas compression pump connected, on the one hand, to the chamber in which the gas of evaporation from the CO₂ collects, and on the other, with a suitable mixer or mixing chamber into which it is delivered by said compression pump to mix 75 with the liquid to be carbonated. In combination with said pump suitable means may be employed for regulating the amount of gas delivered from the pump and also for regulating the delivery of the water or liquid 80 from a liquid pump used in association with the gas pump for supplying the water to the carbonator.

In using solid CO₂ as a refrigerant, if the evaporating is accelerated, a higher efficiency 90 of refrigeration results, but if the CO₂ is used as a refrigerant only, the expense is increased, whereas by utilizing the evaporated CO₂ for subsequent carbonation, the double use makes up for the increased solid CO₂ consumption 95 thereby increasing efficiency all around. And by inclosing the entire proposed construction within a refrigerator, a soda fountain for instance, every possible unit of solid CO₂ efficiency may be utilized to advantage including 100 control of refrigeration, which means evaporation control.

Referring to the accompanying drawings:

Fig. 1 shows in side elevation and partial section apparatus adapted for the practice 105 of my invention.

Fig. 2 is an enlarged vertical section through a part of the apparatus in its preferred form.

At 1, Fig. 1, is indicated a table, shelf or 110 counter forming the top part of a casing or framework while the numerals 2, 3, respectively indicate the outlet pipes for the carbonated liquid and an uncarbonated liquid or plain water to be dispensed or utilized through suitable draft arms or faucets in the usual manner employed, for instance in soda water fountains.

At 4 is indicated a suitable refrigerating or cooling compartment or shell shown more in 115 detail in Fig. 2 and provided with suitable heat insulating walls as indicated at 5. Said container forms a receptacle for the CO₂ ice supported therein preferably in a solid cake upon a suitable tray or horizontal partition 120 6 located at an intermediate point in the height of the inner casing or container 7.

The lower part of the container 7 may form a tank for water which is to be cooled and which may be delivered to the carbonating 125

devices as will be presently described. Said tank is provided with devices for maintaining a constant level of the water or liquid therein, said devices comprising the usual 5 float 8 and valve 9 through which water is supplied from a suitable source, as for instance through the connecting pipes 10, 11, deriving supply from the city water main or other source. Pipe 11 is continued into a pipe 10 having a suitable shut-off valve 13 through which water may be passed directly to the carbonating apparatus in case the supply from the constant level tank described should, for any reason, fail. The delivery of water 15 from the latter tank is through pipe 14 from which it passes to pipe 15 for delivery to the carbonating apparatus. Pipe 12 is connected to pipe 15 through a T-joint, as shown, so that 20 15 may draw its supply either from the tank or directly from the main or pipe 10 as just stated.

Perforations 16 in the container 7 permit the evaporated CO₂ gas to escape into the lower portion of the space surrounding said 25 tank, from which it may pass through the outlet pipe 19 to pipe 20 for delivery to the compression pump employed, as will be presently described, in carbonating the liquid. Other perforations 21 in the side of tank 7 30 permit some of the gas to enter the space above the liquid where it will rest upon the top of the water and will be partially absorbed thereby. As the water supplied to the carbonator gas pump is thus refrigerated it 35 will more readily absorb CO₂ for carbonation due to the fact that, as well known, water will more readily absorb CO₂ at low temperatures.

In the container 4 I prefer to employ two 40 coils through which water may be circulated for cooling by the CO₂ ice. One of these coils, indicated at 22, may be connected directly at one end with the main 10 through a shut-off valve 23 and the riser 24. The other end of 45 said coil is joined in the outlet pipe 24 forming a riser which terminates in the pipe 3. The other coil 25 is supplied with carbonated liquid through a pipe 26 leading from the carbonating apparatus and delivers cooled carbonated liquid to the riser 27 terminating in 50 the outlet pipe or connection 2. Obviously the cooling effect of the CO₂ is expended also in cooling the liquid in said coils and the gas thereby released collects in the lower part of 55 the container for delivery through pipes 19 and 20 to the carbonator.

Gas for the carbonating purposes may be supplied separately or in conjunction with that released in the compartment or container 60 4 by providing a separate compartment 28 in which the CO₂ ice may be employed for refrigerating ice cream packers, as shown, while the gas released from the ice and collecting in said compartment is passed to the 65 pipe 20 through outlet 29 for use separately

or in conjunction with that released in compartment 4.

As will be seen, these devices provide (a) for storage and distribution of the CO₂ gas derived from evaporation of the solid CO₂ 70 employed in a refrigerating enclosure and for passing the gas to the carbonator; (b) for pre-cooling the water supply to the carbonator or to the dispensing outlets or drafts for either carbonated or uncarbonated liquid; 75 (c) provides for a constant pressure or head of the liquid to the carbonator pump whereby a predetermined flow to a mixing chamber may be assured in conjunction with the carbonating gas. By this latter feature the use 80 of a constant pressure diaphragm valve for securing constant flow with a low pressure is avoided, which is very desirable since a valve for such low pressure would have to be abnormally large, say four feet in diameter. 85

At 30 is indicated a gas pump of any desired or usual construction which takes the low pressure gas delivered through pipe 20 preferably from the containers 4, 28, or other suitable source and delivers it for mixture 90 with water delivered from a pump 31 deriving its supply through pipe 15 from any desired source, but, as already described, preferably from the source of cooled water supplied at constant pressure from the water 95 tank in container 4. Pumps 30, 31, are driven in the usual or any desired way from an electric motor 32 or other source of power regulated in its action as will be presently described. 100

On each pump is a gauge 33 indicating the drawing pressure of each. By means of suitable reducing or adjusting valves 34 connected to the outlets of the pumps this drawing pressure may be fixed so that the discharge of each may be controlled as to amount delivered by each in a given time. To enable this to be readily done the dials or scales on the valves 34 may be provided with figures corresponding to the figures on the 105 gauges 33. This enables the proportion of the mixture of CO₂ and water to be fixed or regulated so that the desired amount of each passes forward to the mixer through the union 35 and pipe 36 to a suitable mixer 37, whence the mixture passes through an outlet 38 into a carbonator body 39 wherein the carbonated liquid is stored under pressure 110 ready for delivery through an outlet pipe 40 connecting with the pipe 26 and with the draft arm outlet 2 through, preferably, the cooling coil already described. 115

The mixer may be constructed on the inside with means for assisting in a further mixing of the CO₂ and the water so that when the mixture enters the carbonator body through the pipe 38 it is in proper condition for use. If desired the mixer 37 may be dispensed with and the gas and water delivered 120 125

from the pumps 30, 31, directly into the carbonator body or storage tank 39.

Preferably the operation of the pumps is automatically controlled by the weight of the contents of the container 39. To enable this to be done said carbonator body may be provided with a balancing weight 41 working on suitable guides and sustained upon their balancing levers 42 which receive the weight of the tank. Connected to the levers 42 or to the weight 41 is an arm 43 terminating in a suitable switch box 44 whereby the motor 32 may be stopped and started as the weight rises and falls under the weight of the carbonator 39 and its contents. When the weight decreases by withdrawal of water from the carbonator body through pipe 26 and draft arm, the counterbalancing weight 41 will fall thereby operating the starting switch 44 to cause the pumps to operate and replenish the supply in the tank or carbonator 39. When, through such supply, the weight of the carbonator and its contents increases, the weight 41 will be raised thereby raising the connection 43 and operating the switch to stop the action of the pumps.

At 45 is indicated a pressure responsive device responsive to variations of pressure within the carbonator body. Said pressure responsive device is connected with a suitable lever 46 through which it operates to throw a switch which controls the operation of the pumps by their motor to assure proper pressure in the system at all times. At 47 is indicated a suitable snifting device which operates when the switch acts and serves to prevent the carbonator body or storage tank 39 from becoming gas or air bound.

Obviously the construction described, while designed for and particularly adapted for use when the CO₂ gas and water are supplied under a low pressure and with constant head for water, might be employed in connection with water and CO₂ under pressure to give the desired proportion of CO₂ and water delivery, this desired proportion being secured in any case by initial setting of the pump flows and regulating the valves 34.

The advantages of the construction described are:

(A) Adaptability for operation with extremely low pressures and providing thorough carbonation at the delivery point of the carbonated liquid.

(B) The ability to utilize evaporated solid CO₂ direct from a supply of that material or from an enclosure in which the CO₂ gas liberated by utilizing the CO₂ for refrigeration is collected.

(C) Making it possible to change from high pressure to low pressure carbonation in an emergency.

(D) Ability to adjust the proportions of the mixture of the evaporated solid CO₂ and

water by the dials and gauges that is positive and fixed in its results.

(E) Operation with a minimum of costly leaks and repairs and consequent loss of service.

(F) Carbonation with lowest drum pressure if a drum of CO₂ is used thus utilizing all the CO₂.

(G) Ready control of the proportions of carbonation mixtures.

(H) Delivery of more highly carbonated water.

(I) Utilizing the gases of evaporation of solid CO₂ employed to cool water for carbonation.

As will be seen, the apparatus described constitutes an equipment that is a complete unit in itself and may be used as an attachment to or auxiliary to any present carbonator already in use.

What I claim as my invention is:

1. The combination of a cooler containing CO₂ ice as a refrigerant and adapted to cause the ice to be converted into gas by heat acquired through the cooling operation taking place within said cooler, said cooler being provided with a suitable gas retaining space for collecting the CO₂ gas of evaporation, means for introducing a substance to be cooled into said cooler, a carbonator and means for conveying said gas to and utilizing it as the carbonating gas in said carbonator.

2. The combination with a closed container for CO₂ ice having a gas collecting and retaining space for the gas liberated from the ice of a liquid cooling receptacle below the same and having a space above the liquid in communication with the ice containing space so that the CO₂ gas liberated in the cooling action of the ice may enter the space above the liquid and be absorbed by said liquid.

3. The combination with a refrigerating apparatus employing as the refrigerant a cooling agent which releases a carbonating gas through its cooling action, and provided with a container for said agent having a suitable gas-expanding and collecting space, of a carbonator, a gas compression pump delivering gas to said carbonator and means for conveying the released gas of evaporation from said container to said pump.

4. In an apparatus for cooling and charging liquids with CO₂ gas, the combination of a liquid cooling chamber containing CO₂ ice, a carbonator, a gas compression pump connected therewith, means for conveying the cooled liquid to the carbonator and means for conveying the CO₂ gas liberated in the cooling of the liquid to the compression pump.

5. In an apparatus for charging liquids with CO₂ gas, the combination with a cooler containing CO₂ ice, a liquid cooling chamber therein, means for continually maintain-

ing the level of liquid in the latter, a carbonator, a gas compression pump taking the CO₂ gas liberated in the cooler and delivering it to the carbonator and means for conveying the liquid from the liquid cooling chamber to said carbonator.

6. In an apparatus employing CO₂ ice as a refrigerant, the combination with the ice chamber of a liquid cooler at the bottom of the same provided with openings for conveying the CO₂ gas liberated in the cooling operation to the surface of the liquid therein, a liquid pump connected with the liquid chamber and a gas compression pump to which the CO₂ gas liberated in the cooling is conveyed and means for carbonating the liquid supplied from the liquid pump with gas passed through the compression pump.

7. In an apparatus for cooling and charging liquids with CO₂ gas, the combination of a liquid cooling coil, a suitable cooling chamber therefor containing CO₂ ice, a carbonator connected to a gas compressing pump furnished with CO₂ gas liberated from the ice in said cooling chamber, and means for passing the carbonated liquid through said cooling coil.

8. The combination with a cooling chamber containing CO₂ ice, of a liquid container beneath the same, means for maintaining a constant level of liquid therein, a cooling coil cooled by the CO₂ ice, means for delivering the liquid from said coil to a connection for a dispensing outlet, a carbonator, a gas compressing pump, and a liquid supply pump connected with said carbonator, piping connections for delivering the CO₂ gas liberated in the cooling operation to said compressing pump and means for delivering the liquid cooled in said container to said liquid supply pump.

9. In an apparatus for carbonating and cooling liquids, the combination with a container for CO₂ ice of two coils therein, means for passing uncharged liquid through one of said coils, a carbonator, a gas compression pump connected to said carbonator and deriving CO₂ gas from a supply consisting of the CO₂ gas liberated in the cooling operation, and means for passing the charged liquid from the carbonator through the other of said coils to an outlet pipe or connection.

10. In an apparatus for dispensing carbonated liquids, the combination of a cooler comprising a closed container provided with means for supporting a solid block of CO₂ ice, a mixer, a gas compression pump and a liquid supply pump both connected with said mixer and means for delivering CO₂ gas liberated from the ice in the cooler to the compression pump.

11. In an apparatus for carbonating liquids, the combination with a carbonator tank provided with a gas compression pump and a liquid supply pump, means for auto-

matically starting and stopping the pumps in accordance with variations in the weight of the liquid contained in the carbonator and means for automatically starting and stopping the pumps in accordance with variations in the pressure of the contents of the carbonator.

12. In a cooling and carbonating apparatus, the combination of a cooling chamber adapted to collect the CO₂ gas liberated from CO₂ ice contained therein, a water tank within said apparatus the water of which is exposed to the CO₂ gas liberated in said chamber means for carbonating a liquid by the liberated CO₂ gas and two individual cooling coils in said chamber one for uncarbonated water or liquid and the other for carbonated liquid carbonated by liberated CO₂ gas.

13. The combination with a carbonator, a gas pump constructed for delivering gas to said carbonator, a cooler containing solid CO₂ ice as a cooling agent, said cooler being provided with a chamber for collecting and retaining the CO₂ gas liberated from the ice and means for supplying to said gas pump the CO₂ gas liberated by the evaporation of said CO₂ ice.

14. The combination with a cooling chamber sealed and provided with means for supporting solid CO₂ ice and having a space therein adapted to collect CO₂ gas liberated from CO₂ ice used therein, a carbonator for carbonating a liquid and means for withdrawing said CO₂ gas from said space and forcing the same into said carbonator.

15. The combination with a cooling chamber provided with means for cooling a liquid and adapted to collect CO₂ gas liberated from CO₂ ice used therein, of a carbonator, a liquid pump deriving its supply of liquid from said cooler and a gas pump delivering the liberated gas to the carbonator and charging said liquid with said gas.

16. The combination with a sealed cooler provided with means for supporting solid CO₂ ice and adapted to collect CO₂ gas liberated from CO₂ ice therein, of a gas pump connected with said cooler for charging a liquid with said liberated CO₂ gas and means for regulating the supply of gas from the pump for carbonating purposes.

17. In an apparatus for carbonating liquids, the combination of a gas pump, a water pump, means for delivering to the water pump water cooled by CO₂ ice, means for delivering to the gas pump CO₂ gas liberated in the cooling action, a mixer into which the output of the two pumps is delivered for carbonating the liquid and a storage tank or body into which the output from the mixer is fed.

18. In a cooling and carbonating apparatus the combination of a sealed container containing CO₂ ice in solid form, means for

passing a liquid through the container to evaporate the ice, means for carbonating a liquid and means for conveying the gas in said container released by the evaporation of said ice to the carbonating means.

3 19. In an apparatus for cooling and carbonating liquids the combination of a cooling refrigerating container for solid CO₂ ice, means for passing a fluid to be cooled through said container for cooling by the evaporation of said ice and means for carbonating liquid by the CO₂ gas liberated from the solid CO₂ ice in the cooling operation.

15 20. In an apparatus for cooling and carbonating liquids, the combination with a cooling or refrigerating chamber containing a cooling agent which liberates a liquid charging gas in its cooling operation and provided with a gas collecting and retaining space, means for passing liquid to be charged through said chamber in order to cool the same, a charging device, means for conveying the cooled liquid to said charging device and means for conveying the released gas to said charging device for charging said liquid.

30 21. In a refrigerating and gas charging apparatus the combination of a cooler adapted to support a block of ice which vaporizes by heat absorbed in the cooling operation within the cooler and thereby liberates charging gas, means for introducing a substance to be cooled into said cooler, said cooler being provided with suitable gas retaining spaces in which the liberated gas may expand and collect, a charging device and means for withdrawing said liberated gas from said cooler and utilizing it in the said charging device for charging a liquid.

35 40 Signed at New York in the county of New York and State of New York this 20th day of March A. D. 1928.

HARRY S. CORNISH.
